ROLLER SKATE

Max Wilhelm Schmid, St. Gallen, Switzerland,
assignor to Paul Steiger, Herisau, SwitzerlandApplication September 11, 1948, Serial No. 48,826
In Switzerland May 9, 1946

11 Claims. (Cl. 280—11.23)

1

This invention relates to roller devices or skates with supporting plates or platforms for the engagement of the foot or feet of a person.

According to the invention the wheels or rollers of the device have ball-shaped or spherical running surfaces and are supported relatively to the plate, platform or the like by means of axle forks or the like which are so shaped that the lower parts thereof will be disposed together with securing means therefor in the outer ends of the bearing bushes or hubs carried by said rollers, said bushes or hubs being recessed within the rollers and the arrangement being such that the maximum inclination of the device may be obtained when taking curves, performing arcs or figures and the like.

In order that this invention may be clearly understood and readily carried into effect the same will be hereinafter more fully described with reference to the accompanying drawing which illustrates certain embodiments of the invention by way of example and in which—

Figure 1 shows in side elevation a roller skate constructed in accordance with the invention;

Figure 2 is a rear view of the skate shown in Fig. 1 in inclined position assumed when taking a curve;

Figure 3 is a bottom plan view of the rear part of the roller skate shown in Fig. 1;

Figure 4 is a section through the rear part of the roller skate taken on line 4—4 of Fig. 1;

Figure 5 is a side view of a modified roller skate constructed in accordance with the invention.

Referring to the annexed drawing, 1 indicates the supporting plate or platform of a roller skate, which is provided at its rear end with a holder 2 adapted to receive the heel of a boot, the fore part of said plate 1 carrying a pair of clamping jaws 3 adapted to engage the sole of the boot in known manner. The jaws 3 are adapted to be adjusted by means of a screw having right and left-hand threads and are secured from shifting longitudinally of the platform.

4 and 5 indicate rubber rollers with circular- or ball-shaped running surfaces while 6 and 7 are forked axle brackets. The front axle brackets 6 are fixed on the supporting plate 1, while the forked rear axle brackets 7 are fixed by screws 10 to a plate 9 which, in turn, is rotatable about a pin or pivot 8 whereby lateral and parallel displacement of plate member 9 relatively to the supporting plate 1, as seen in Figs. 2 and 3. The upper part of the pin 8 riveted into the supporting plate 1, while the lower part carries a

nut 11. The lower parts of the axle brackets 7 are inwardly bent in the manner illustrated in Fig. 4 the bent parts of the brackets being disposed within the hollow ends 13 of the bearing bush or hub 14 (Fig. 4).

The bearing axle is indicated by 15 and its length is such that it may be accommodated within the bearing bush 14. The axle 15 is secured in position within the axle bracket extensions by means of nuts 15a which also come to be located within the bearing bush 14. Two ball bearings 17 spaced from each other by a spacer sleeve 16 are fitted on and support the bearing axle 15, the outer ball races of said bearings being connected to the bearing bush 14.

The bearing bush 14 is embraced over its whole length by the roller 5 which latter is formed of rubber, is flattened at its sides or lateral end portions and is seated on to the bearing bush 14. 20 This structure also applies to the roller 4. Owing to the width of the rollers which amounts, for example, to 5 cm. there is no danger that the rubber body fixed on to the bearing bushes might become loose on account of heavy stresses caused by moving in inclined position round curves. In the same way, the rubber prevents any danger of outward slipping.

It is to be noted, that the rubber body of each roller consists of spherical or ball-shaped portions, each of which has a radius with the center thereof disposed a predetermined distance from the center of the horizontal axis passing through axle 15. The distance between the centers of the radii for said spherical portions is relatively smaller than the radius of each of said ball-shaped or spherical portions, so that an approximate ellipsoidal body is achieved, which has an opening for the insertion of the bush 14, whose diameter is smaller than the distance between the flattened lateral side portions of the roller body.

The plate 9 is provided at its forward part with an eye 18 to which are fixed, by means of a nut and bolt 19, two steel strips 20 and 21 arranged to form the letter V which strips extend towards the centre of the roller skate and are located underneath the supporting plate 1. The free ends of the steel strips or similar spring guide means 20 and 21 are bored and connected together by a spacer screw device 22 provided with head and nut (Fig. 3). In addition the supporting plate 1 is formed with a slot 23 in which a longitudinally adjustable abutment pin 24 is supported said pin carrying a nut 25 by means of which it may be secured in position after adjustment. The pin

24 also carries means, such as a washer 26 and a second nut 27 by virtue of which the free ends of the steel strips 20 and 21 are supported and the effective length of said steel strips may be adjusted with respect to the plate member 1.

In the example according to Fig. 1, only the rear roller 5 is arranged to be laterally displaceable, the front roller 4 being fixed. The displacement of the roller 5 is illustrated both in Fig. 2 and also in Fig. 3 (see dotted position of plate 9 about pivot 8). It is clear from Fig. 2 that the roller skate in running on a curve can assume an inclination of 30 degrees to the horizontal. In a racing type of roller skate, however, the rear half band or holder 2, in which the heel of the boot is normally disposed, is dispensed with and the boot is simply screwed on to the supporting sole 1. In this case, the roller skate can assume an inclination of 25 degrees to the horizontal in running on a curve, without the forked axle bracket extensions or their fastening means (bearing axle 15 with nuts) or any other parts of the roller skate coming into contact with the ground.

According to the embodiment illustrated in Fig. 5, in addition to the rear roller, the front roller 28 is also mounted in such a manner as to be displaceable. In this case, the forked axle brackets are mounted on a plate 30 which is in turn capable of pivotal movement about a pin 29 carried by the supporting plate 1 and having a threaded retaining nut thereon. The plate 30 is adapted to carry an eye 31 to which two steel strips 32 are connected said strips being located underneath the supporting plate 1 and relatively so disposed as to form a V-shape (similar to the construction explained with respect to Fig. 3). In Fig. 5 one of the strips 32 only is visible. The ends of the steel strips 32 have openings, similarly to the oppositely located ends of the rear steel strips 20 and 21, for the purpose of being inter-connected by means of a spacer screw. In addition the supporting plate is formed with a slot (not shown) in which a stop pin 33 is supported in such a manner as to be longitudinally adjustable. The lengths of the front and rear steel strips 32 and 20, 21 are so dimensioned that the opposing free ends thereof will be clear of each other (Fig. 5).

As the rollers have running surfaces of ball shape and as they are furthermore arranged so as to be capable of lateral displacement in a plane parallel to the platform or supporting sole, the displacement of said rollers and also the movement thereof from the displaced position (Fig. 3) to the normal position takes place easily. On displacement of the rollers each pair of steel strips of V-form curves outwardly between their point of fixation and the abutment pin either one side or the other according to whether a right or left-hand curve is traversed.

The invention is not limited in its application merely to roller skates since it can also be applied to other devices of a kindred nature wherein all or certain of the rollers employed may be so mounted as to be capable of displacement or not as required.

The rollers themselves may, instead of being formed of rubber, be formed of any suitable material, e. g., of wood or of a plastic substance. Having thus described the invention, what is claimed as new and desired to be secured as Letters Patent, is:

1. A roller skate device comprising a supporting platform for engagement with the foot of a

person, a member mounted for angular movement relatively to said platform, a pair of roller-supporting forked brackets provided with extensions and depending from said member, a pair of resilient strip elements also associated with said member, a stop adjustable longitudinally of said platform with which said strip elements are adapted to cooperate to determine the angular position of said member relatively to said platform, and a roller having a ball shaped outer surface and rotatably supported by said brackets, said bracket extensions being shaped to project laterally into said roller.

2. A roller skate device comprising a supporting platform for the skater's foot, a first pair of axle supporting forks rigidly mounted at the underside of said platform, a member mounted for pivotal movement at the underside of said platform, a second pair of axle supporting forks carried by said member, a pair of resilient strip elements associated with said member, a stop adjustable longitudinally of said platform with which said strip elements are adapted to cooperate to determine the angular position of said member with respect to said platform, an axle carried by each pair of forks, a roller supported by each axle, each roller having a ball-shaped outer surface, and a bearing bush located within each roller and accommodating therein the respective axle to allow rotation of the roller thereabout, each pair of supporting forks being provided with inwardly bent ends for engagement with a respective axle, whereby said bent ends and said respective axle are located within said bearing bush.

3. A roller skate device comprising in combination a supporting platform for the foot of the skater, a pair of plate members spaced from each other and mounted for angular movement at the underside of said platform, a pair of axle supporting forks carried by each member and arranged to extend below said member and said platform, a pair of resilient strip elements also associated with each member, a pair of stops each adjustable longitudinally of said platform and with each of which one pair of resilient strip elements is adapted to co-operate to determine the angular position of each member with respect to said platform, an axle carried by each pair of forks, a roller supported by each axle, each roller having a ball shaped outer surface, a bearing bush located within each roller and accommodating therein a respective axle to allow rotation of the roller thereabout, each pair of supporting forks being provided with extensions bent to engage a respective axle supported thereby.

4. A roller skate device comprising a platform for engagement with the foot of the skater and provided with an elongated slot, at least one substantially ball-shaped roller means having central recesses and arranged to extend below said platform, an axle having opposite ends supporting said roller means for rotation, a plate member, a pivot connecting said plate member with said platform whereby said plate member may be displaced in a direction transversely to said platform about said pivot, bracket means provided with extensions and carried by said plate member, said axle of said roller means being supported by said extensions receiving the ends of said axle, said axle ends and said extensions of said bracket means being contained within said recesses of said roller means, springy guide means anchored to said plate member and extending therefrom to said slot, and a pin engaging said

slot and linked to said guide means, whereby said plate member during displacement about said pivot is guided by said springy guide means relatively to said slot.

5. A roller skate device according to claim 4, wherein said one roller means is disposed adjacent one end of said platform, and a further roller means is arranged for position adjacent the opposite end of said platform, said one roller means being displaceable in lateral direction to said further roller means and in a plane substantially parallel to the plane of the axis of said further roller means.

6. A roller skate and like propulsion device comprising an elongated platform for engagement with the foot of the skater and provided with a slot extending lengthwise of said platform, ball-shaped roller means including an axle and arranged to extend below said platform, a movable plate member, a pivot connecting said plate member with said platform therebelow whereby said plate member may be displaced from normal position in a direction transversely of said platform about said pivot, bracket means associated with said plate member and supporting said axle of said roller means whereby the latter may rotate about said axle, and springy guide means connected to said plate member and extending for engagement with said slot of said platform, said springy guide means being adapted to permit displacement of said plate member about said pivot and to serve to return said plate member to said normal position.

7. A roller skate and like propulsion device comprising an elongated platform for engagement with the foot of the skater and provided with a slot extending lengthwise of said platform, ball-shaped roller means including an axle and arranged to extend below said platform, a movable plate member, a pivot connecting said plate member with said platform therebelow whereby said plate member may be displaced from normal position in a direction transversely of said platform about said pivot, bracket means associated with said plate member and supporting said axle of said roller means whereby the latter may rotate about said axle, and steel strip means connected to said plate member and engaging said slot of said platform to thereby maintain said plate member in said normal position with respect to said platform.

8. A roller skate and like propulsion device according to claim 7, including a pin movable

within said slot of said platform and linked to said steel strip means, and means carried by said pin for adjusting the effective length of said steel strip means with respect to said plate member.

9. A roller skate and like propulsion device according to claim 7, wherein the axis of said pivot is perpendicular to the axle of said roller means.

10. A roller skate and like propulsion device according to claim 7, wherein said bracket means are provided with inwardly projecting extensions by which said axle of said roller means is supported, said roller means being provided with recesses in which said extension means and said axle are accommodated, the outer surface of said roller means extending beyond the ends of said axle.

11. In a rollable support for engagement with the foot of a person; comprising at least one roller body having a sleeve with opposite ends, and an axle accommodated in said sleeve, said roller body including spherically shaped surface portions continuing up to the opposite ends of said sleeve, the respective centers of said spherically shaped surface portions being disposed a predetermined distance from each other and from the center of the horizontal axis of said axle of said body, the distance between said centers of said surface portions being relatively smaller than the radius of each of said spherically shaped portions, and opposite flattened side portions on said body through which said axle extends, the extent of said flattened side portions substantially coinciding with said opposite ends of said sleeve.
